UNITED STATES PATENT OFFICE.

FAVILLE A. TROW, OF ALBERT LEA, MINNESOTA.

LIQUID-FUEL BURNER.

Application filed November 5, 1924. Serial No. 747,953.

My invention relates to liquid fuel burners adapted particularly for stoves and has for its object to provide improved means for quickly heating the wall of the retort so that vaporization of the fuel and use of the burner may be obtained in a much shorter space of time than when the ordinary or conventional priming cup is used.

A further object is to provide a simple inexpensive adjunct to the burner which will not add materially to its cost and can be incorporated without very much expense in a burner that is already constructed and in use, thus providing a wide field of usefulness for the device.

The invention consists generally in various constructions and combinations all as hereinafter described and particularly pointed out in the claims.

20 In the accompanying drawings forming part of this specification,

Figure 1 is a plan view of a liquid fuel burner embodying my invention mounted in a stove casing or frame;

25 Figure 2 is a longitudinal sectional view through an auxiliary vaporizing pan and the fuel feed therefor;

Figure 3 is a transverse sectional view through the auxiliary vaporizing pan and a portion of the burner.

30 Figure 3^a is a sectional view on the line 3—3 of Figure 2;

Figure 4 is a longitudinal sectional view through the valve and its connections for controlling the delivery of the liquid fuel to the auxiliary vaporizing pan;

Figure 5 is a detail enlarged view of the orifice of the valve shown in Figure 4.

35 In the drawing, 2 represents a portion of a casing or frame, 3 a burner grid mounted therein, 4 a liquid fuel supply tank in which the liquid fuel is contained under pressure, and 5 a burner located below the grid. 6 is a retort pipe mounted horizontally in the casing or frame 2 and extending over the burner 5 adjacent thereto and having its inner end connected to a trunk 7 which leads down under and communicates with the burner for supplying the vaporized fuel thereto.

40 The trunk or pipe 7 has an air intake 8 and the retort pipe 6 has a valve seat 9 and a valve 10 having a threaded connection at 11 with the inner wall of the retort.

45 The valve 10 has a needle 12 forming a continuation thereof and projecting into the

air trunk 7. The stem 13 of the valve 10 has a hand grip 14 and is spaced from the wall of the retort to form a liquid fuel passage 15 and a pipe 16 connects the pressure tank 4 with the retort so that when the valve 10 is opened the fuel may flow through the retort, being vaporized in its passage and discharged into the mixing chamber of the trunk 7. This portion of the apparatus is 60 common to burners of this type in general use.

50 My improvement consists in providing a cup or pan 17 made preferably of a suitable casting having an upright end baffle wall 18 that is beneath and near the retort pipe 6

for directing a vaporizing flame against the surface of said retort to heat the same preparatory to the use of the burner. The cup 17 preferably has a bracket 19. A valve 70 casing 20 is mounted in the frame or jacket of the stove casing and has a pipe connection 21 with the bracket 19. A valve seat 22 is provided in the valve casing 20 and a stem 25 which projects inwardly within a tube 26 in the pipe 21 terminates in a needle point 27 that is fitted within an orifice 28 in a head 29. The valve 24 has an operating handle 30 and the valve casing 20 has an intake duct which communicates through a pipe 32 with the retort pipe 6 so that whenever there is a pressure in the tank 4 the liquid fuel will be forced through the pipe 16 into the retort 6 and from thence 80

through the pipe 32 to the space in the valve casing 20 around the valve 24. When the valve 24 is opened, the liquid fuel under pressure will be forced through the tube 26 and before opening the valve 24 the tube 26 and the needle point are heated by a 85

match or candle flame to a point which will cause vaporization of the liquid fuel when the small stream flows through the tube 26 upon opening the valve 24. The vapor discharged around the needle point 27 upon ignition will be projected in the form of a blue flame against the baffle wall 18 and the shape and position of this wall are such that the blue flame will be directed or deflected 90

against the adjacent portion of the retort pipe 6 and will also flow backwardly around the exposed end of the tube 26 and maintain the walls of this tube at a fuel vaporizing temperature and continue the vaporization of the small stream of fuel, the tube 26 acting as an auxiliary or supplementary retort 100

105 continuing the vaporization of the fuel un- 110

til the valve 24 is closed. The operation of the auxiliary retort is continued until the retort 6 is heated sufficiently for vaporizing purposes and at such time the valve controlling the flow of fuel through the main retort to the burner is opened and when the burner is ignited by the flame from the auxiliary retort the main retort will be kept at a vaporizing temperature by the burner flame and the auxiliary or supplementary retort may be cut off by the closing of the valve 24. The needle point and supplementary retort are positioned a sufficient distance from the baffle wall to obtain the proper mixture of air and vaporized fuel to produce the desired blue heating flame, and the baffle wall is so shaped that it will cause the blue flame from the auxiliary retort to encircle and envelope a portion of the main retort and insure the very quick heating of the same while the backward flow of this blue flame will maintain the forward portion of the tube 26 at the desired temperature for vaporizing the fuel flowing therethrough. This vaporizing in the auxiliary retort will continue until its feed valve is closed. The bottom of the pan 17 is formed so that it will concentrate the flame upon the wall of the retort above. The needle point 27 has the particular function of preventing the orifice in the head 29 from becoming clogged with foreign or refuse material which may be carried along in the liquid fuel.

35 In the use of the device, the operator will first provide suitable pressure on the liquid in the pressure tank. Then before opening the valve 24, he will heat the projecting end of the tube 26 by means of a match or candle flame. Then the valve 24 is opened and as the small stream of liquid fuel flows toward the orifice 28, it will instantly become vaporized and upon ignition will throw a blue flame against the baffle wall 18 from whence 40 the flame will be deflected upon the retort 6 above and backwardly from the tube 26 to continue the heating of the same and cause it to become a temporary auxiliary retort for vaporizing the fuel used in heating the main retort. Generally, a priming pan is provided adjacent the main retort and the liquid fuel therein is ignited and allowed to burn in a white flame and several minutes are required to heat the main retort sufficiently to vaporize the body of fuel therein. With my improvement, the time consumed in waiting for the main retort to become heated is practically eliminated. The small body of liquid fuel flowing through the tube 45 26 when the valve 24 is opened is instantly vaporized by the heated walls of the tube and a blue intense heating flame is immediately provided and projected against the walls of the main retort so that in a very short period of time after the match or other

flame is applied to the tube 26 the blue heating flame is formed and the main retort is heated and ready for vaporizing the main body of fuel.

I claim as my invention:

1. The combination with a burner and retort, of an auxiliary retort and means for delivering thereto a small quantity of liquid fuel under pressure, said auxiliary retort being adapted when heated by a small flame to 70 vaporize such small quantity of liquid fuel, and means adjacent said main retort for directing the flame from said auxiliary retort upon the walls of said main retort, and deflecting said flame upon said auxiliary retort to continue the vaporizing of the fuel therein.

2. The combination with a burner and retort, of an auxiliary retort and means for delivering a small body of liquid fuel thereto, the walls of said auxiliary retort being adapted to be initially heated by the flame of a small heating means for vaporizing the liquid fuel therein, and a pan having a baffle wall opposite said auxiliary retort, to deflect the flame of the vaporized fuel from said auxiliary retort upon said main retort and against the wall of said auxiliary retort to 80 continue the vaporizing therein.

3. The combination with a liquid fuel burner, having a main retort pipe and a tank for supplying liquid fuel under pressure thereto, of an auxiliary retort connected with said tank and having a valve and nozzle and adapted to be initially heated by a small flame to vaporize a stream of liquid fuel when said valve is opened, said auxiliary retort being spaced from said main retort, and means for directing the flame when the vapor from said auxiliary retort is ignited 90 upon the wall of said main retort and upon said auxiliary retort to continue the heating of its walls and the vaporizing of the fuel until said valve is closed.

4. The combination with a burner and main retort the latter having a nozzle, of an auxiliary retort, the main retort passing over and beyond said burner, the auxiliary retort being also located approximately beneath said main retort, said auxiliary retort opening into a cup or pan which extends under the auxiliary retort and under the main retort and arranged to direct the flame from the auxiliary retort up and around the main retort and also under the auxiliary retort, whereby the flame from the auxiliary retort is directed against the walls of the main retort and against the auxiliary retort to continue the vaporizing of the fuel therein.

5. A main and auxiliary retort for a burner, the main retort passing over the burner and at one side, a trunk for the vaporized fuel at the end of the main retort extending horizontally thence downwardly

- and back and to an opening therein under the main retort and burner with an air intake connecting with said main retort, the auxiliary retort having a cup-shaped vessel resting above said trunk for causing the flame of the auxiliary retort to pass around the main retort and in contact with the auxiliary retort.
6. A burner comprising a main retort, a trunk for vaporized fuel at the end of the main retort, said trunk extending horizontally, thence backwardly under the main retort and having a burner on its end, an auxiliary retort having a flame directing device stationed in proximity to the main retort to direct the flame from the auxiliary retort against the main retort and against the auxiliary retort.
7. An auxiliary retort for a burner comprising an outer casing having a valve seat therein, an inner casing having a needle valve extending therethrough, and a valve cooperating with the valve seat, the inner casing extending through and beyond the outer casing to furnish a small surface easily heated.
8. The combination with a burner, a main retort, the latter having a nozzle, of an auxiliary retort, the main retort passing over said burner, the auxiliary retort being also located in proximity to said main retort, said auxiliary retort opening into a cup or
- pan which is arranged in proximity to the auxiliary retort and the main retort and is arranged to direct the flame from the auxiliary retort against the main retort and also against the auxiliary retort to heat the same.
9. A main and auxiliary retort for a burner, the main retort passing over the burner and at to one side, a trunk for the vaporized fuel at the end of the main retort extending horizontally, thence downwardly and backwardly to an opening therein under the main retort and burner with an air intake opening into the main retort, the auxiliary retort having a cup-shaped vessel resting above said trunk for causing the flame of the auxiliary retort to pass against the main retort and against the auxiliary retort to keep the latter warm.
10. A burner comprising a main burner and an auxiliary burner, the auxiliary burner comprising an outer casing, an inner casing, the inner casing extending through and beyond the outer casing and having a burner at its end, the extended portion of the auxiliary burner furnishing a small surface easily heated, and means to direct the heat of the auxiliary burner to heat said small surface.

In witness whereof, I have hereunto set my hand this first day of November, 1924.

FAVILLE A. TROW.
